UNITED STATES PATENT OFFICE

WILLIAM H. REEVES, OF ST. LOUIS, MISSOURI

PUMP

Application filed November 25, 1927. Serial No. 235,699.

This invention relates to improvements in pumps of the type used for receiving or handling returns, consisting chiefly of condensate and air, from steam heating systems, steam condensers, and other vapor apparatus, of the same general class as shown by my prior Patent No. 1,505,165, granted August 19, 1924.

One of the objects of this invention is to provide an improved means for regulating and varying the amount of condensate handled by the water pump so that condensate will be pumped continuously at whatever rate it may drain to the apparatus from the return pipe; and at the same time maintain a constant water level in the hot well, thereby preventing air or vapor from entering the water pump with the condensate through the suction which could interfere with the normal action of the pump, or cause it completely to fail by becoming "air bound" or "vapor bound"; and to accomplish this result without resorting to intermittent operation.

Another purpose of this invention is to separate the air and condensate as fully as possible and to maintain the separation by bringing the water to rest, or almost so, in the hot well, and by maintaining a definite water seal over the suction of the water pump, in order that the condensate may be returned to the boiler with the minimum air content. With most types of combined vacuum and condensate pumping units in common use on vacuum heating systems the air and condensate are separated in a receiving tank, but are afterwards mixed by recirculating the condensate in some form of hydraulic vacuum pump. While some sort of secondary separation might be attempted it is inevitable that with this continuous recirculation and thorough churning of the condensate and air the condensate as fed to the boiler is highly charged with air. The presence of air in boiler feed water is detrimental in several respects, a principal one, perhaps, being the pitting effect on steel used in the construction of boilers, economizers, pipes and other elements of the plant. In modern central stations for generating electricity the advantages of a small air content

in boiler feed water are so important that deaerators are commonly used for eliminating as much air as possible from the feed water.

Another object of my invention is to overcome all of the difficulties and objections above mentioned and others encountered in the use of the usual pumps, and to obtain other useful results and advantages, all of which will be apparent from the following description, reference being made to the drawings, in which

Fig. 1 is a plan view illustrating one form of the present invention.

Fig. 2 is a side elevation thereof.

Fig. 3 is an elevation, partly in section, illustrating the hot well, float and automatic valve located in the condensate pump discharge with mechanical connection between and float and an automatic valve.

Fig. 4 is a plan view of the invention showing the principal elements thereof arranged in a different relationship from the relationship in which they are shown in Figs. 1, 2 and 3.

Fig. 5 is a plan view showing the principal elements arranged in still another relationship.

Fig. 6 is an enlarged section of the governor controlling the valve in the suction pipe between the vacuum pump and the hot well.

Fig. 7 is an enlarged section of the automatic valve located in the condensate pump discharge.

In a preferred embodiment of the invention as illustrated the principal elements comprise the hot well 1, the centrifugal hot well pump 2, the reciprocating vacuum pump 3, the worm gear drive 4 and the motor 5, all supported upon a common bedplate 6. The hot well 1 is preferably supported horizontally.

Flexible couplings 7 are provided for driving cooperative parts of the shafts 8, 9 and 10. The shaft 8 is from the motor 5 to the worm gear drive 4, the shaft 9 is from the worm gear drive 4 to the centrifugal condensate pump 2, and the shaft 10 is from the worm gear drive 4 to the reciprocating vacuum pump 3. Just as the construction of the internal mechanism of the motor 5 is so well

understood that no detailed illustration thereof is required, so also is the construction of the internal mechanisms of the centrifugal condensate pump 2, the reciprocating vacuum pump 3 and the worm gear drive 4 so well 5 understood that no detailed illustrations thereof are needed.

The hot well 1 receives the returns of the condensate and air through an inlet opening 11, and for the condensate has an outlet passage 12 leading to the centrifugal condensate pump 2. An opening 13 from the hot well 1 above the level of the condensate constitutes an outlet for air to a suction pipe 14 leading to the vacuum pump 3. A vacuum governor 15 controls the valve 16 in the suction pipe 14 leading from opening 13 to the vacuum pump 3 (Figs. 2, 4, 5 and 6). The space below the diaphragm 17 of the vacuum governor 15 has an opening 18 which is connected by a pipe 19 with the air suction pipe 14 between the valve 16 and the outlet opening 13 in the hot well 1. The governor 15 functions to regulate the rate of flow of air from the hot well to the vacuum pump 3 requisite for the desired vacuum at which the governor 15 may be set and at the same time permits the vacuum pump 3 to run continuously at uniform speed. This results in a saving of power approximately 25 in proportion to the reduction in quantity of air handled below the maximum capacity of the vacuum pump 3.

The centrifugal condensate pump 2 may be of any preferred or well understood construction and will remove the condensate 35 from the hot well 1 and discharge the condensate through an outlet passage 20 leading to the boiler or other point of disposition. By this invention the capacity of the centrifugal condensate pump 2 is controlled automatically 40 to correspond with the inflow into the hot well 1 at varying rates of flow, thus maintaining almost a constant water level in said hot well 1, and providing a positive water seal over the suction passage 12 leading to the 45 condensate pump 2. This is accomplished by means of the float 21 in the hot well 1, the float lever 22, the rock shaft 23 to which the float lever 22 is connected, the lever 24 on said rock shaft, and connected by a link 50 25 with a lever 26 pivotally supported on a link 27. The automatic valve 28 has a stem 29 connected with said lever 26 as shown. Figs. 2 and 3 show float 21 in extreme low position 55 in the hot well 1 which is its position when said hot well is empty, and when in which position the automatic valve 28 is closed. As the condensate begins to fill the hot well 1 the float 21 will rise with the water level and 60 cause an upward movement of the float lever 22 which will partially rotate the rock shaft 23 and move the bell crank 24, the link 25 and the fulcrum lever 26, which movement of said fulcrum lever 26 will pull the stem 29 of the 65 automatic valve 28. This movement of the

stem 29 will move the valve element 30 (Fig. 7) from its seat 31 and thus permit the condensate pump 2 to remove condensate from the hot well 1 and discharge the condensate through the automatic valve 28. If the condensate entering the hot well 1 should reach its maximum rate of flow the automatic valve 28 will open proportionately, thus permitting the centrifugal condensate pump 2 to remove the condensate at its maximum capacity. At varying rates of flow of condensate into the hot well 1 the float 21 will vary its position at different levels of the condensate in said hot well and, in turn, control the extent of opening of the automatic valve element 30, and thus limit the pumping of condensate by the centrifugal condensate pump 2 to correspond to the rates of flow of the condensate into the hot well 1. A saving in power will result from the throttling effect as the power used and required to drive the centrifugal condensate pump 2 will decrease approximately in proportion to any reduction in the rate of pumping.

Obviously the vacuum pump 3 need not be limited to the reciprocating type as illustrated, nor is it essential that the condensate pump 2 be of the centrifugal type illustrated, as any form of pump could be used having such characteristics that the capacity may be varied while the pump operates or runs at uniform speed. Also there are many forms of commercial valves which could be used in place of the type illustrated for the automatic valve 28.

While the assembly and relationship of parts above described may be deemed preferable I do not restrict myself thereto, since it is obvious that the assembly may be varied. For instance, as shown in Fig. 4, the motor 5 has a double driving shaft extension 8 and is placed in the center of the group, the condensate pump 2 being directly connected to one end of the motor shaft 8 and the worm gear drive 4 having its shaft 32 directly connected to the other end of said motor shaft 8, while the shaft 10 of the vacuum pump 3 is directly connected to the gear shaft 33 of the worm gear drive 4.

Or, the parts may be assembled as shown in Fig. 5, in which the condensate pump 2 having double shaft extension 9 is placed in the center of the group, one end of the pump shaft 9 being directly connected to the motor shaft 8 and the other end of said shaft 9 being directly connected to the worm shaft 32. In this arrangement the gear shaft 33 of the worm gear drive 4 is directly connected to the shaft 10 of the vacuum pump 3.

From the foregoing it will be seen that the invention constitutes a compact assembly in which the principal elements perform their duties in a highly efficient manner, overcoming all of the disadvantages and objections hereinbefore mentioned and acting automati-

cally when in use. I contemplate such variations as may be made within equivalent limits and do not restrict myself unessentially, but what I claim and desire to secure by Letters Patent is:—

5. 1. A pumping unit comprising a liquid reservoir, a liquid pump having an inlet passage for withdrawing liquid from said reservoir and also having a single discharge passage for expelling from the unit all of the liquid passing from said reservoir through said inlet passage to said pump, a float in said reservoir, and a throttle valve in said discharge passage from said pump mechanically operated by said float for controlling the capacity of said pump to correspond with the rate of liquid inflow to said reservoir.
10. 2. A pumping unit comprising a liquid reservoir, a liquid pump having an inlet passage for withdrawing all of the liquid directly from said reservoir and also having a single discharge passage for expelling from the unit all of the liquid passing from said reservoir through said inlet passage to said pump, a valve in said discharge passage from said pump for controlling the capacity of said pump, an actuator under control of the liquid in said reservoir, and mechanical connections operated by said actuator for operating said 15 valve to control the capacity of said pump to correspond with the rate of liquid inflow to said reservoir.
20. 3. A pumping unit comprising a liquid reservoir, a liquid pump having an inlet passage for withdrawing all of the liquid directly from said reservoir and also having a single discharge passage for expelling from the unit all of the liquid passing from said reservoir through said inlet passage to said pump, a 25 valve in said discharge passage from said pump for controlling the capacity of said pump, an actuator under control of the liquid in said reservoir, and mechanical connections operated by said actuator for operating said 30 valve to control the capacity of said pump to correspond with the rate of liquid inflow to said reservoir.
35. 4. A pumping unit comprising a liquid reservoir, a liquid pump having an inlet passage for withdrawing all of the liquid directly from said reservoir and also having a single discharge passage for expelling from the unit all of the liquid passing from said reservoir through said inlet passage to said pump, a throttle valve in said discharge passage from said pump controlling the capacity of the pump to withdraw liquid from said liquid reservoir and to discharge said liquid through said discharge passage, a float in said 40 reservoir, and mechanical connections operated by said float for operating said valve to vary and to control the capacity of said pump to correspond with the rate of liquid inflow to said reservoir.
45. 5. A pumping unit comprising a liquid reservoir, a liquid pump having an inlet passage for withdrawing all of the liquid directly from said reservoir and also having a single discharge passage for expelling from the unit all of the liquid passing from said reservoir through said inlet passage to said pump, a float in said reservoir, and means in said discharge passage from said pump mechanically operated by said float for controlling the capacity of said pump to withdraw liquid from said reservoir through said inlet passage to correspond with the rate of liquid inflow to said reservoir and to discharge said liquid through said discharge 55 passage.

5. A pumping unit comprising a liquid reservoir, a liquid pump having an inlet passage for withdrawing all of the liquid directly from said reservoir and also having a single discharge passage for expelling from the unit all of the liquid passing from said reservoir through said inlet passage to said pump, a throttling valve in said discharge passage from said pump for controlling the capacity of said pump to withdraw liquid from said reservoir and to discharge said liquid through said discharge passage, a float in said reservoir under control of the liquid in said reservoir, and a mechanical drive connecting said float with said valve for operating said valve by said float to control the capacity of said pump to withdraw liquid from said reservoir to correspond with the rate of liquid inflow to said reservoir and to discharge said liquid through said discharge passage.

6. A pumping unit comprising a liquid pump with an inlet passage for conducting all of the liquid to said pump and a single discharge passage for expelling from the unit all of the liquid received by said pump from said inlet passage, a valve in said discharge passage from said pump, a reservoir connected with and supplying all of the liquid to said inlet passage, a float in said reservoir under control of liquid in said reservoir, and a mechanical drive connecting said float with said valve for operating said valve solely by the power of said float to control the capacity of said pump to correspond with the rate of liquid inflow to said reservoir from a source of supply, and to discharge said liquid through the said discharge passage.

7. A liquid pumping system comprising a vessel containing liquid and air, a liquid pump for removing liquid from said vessel, an evacuator for removing air from said vessel, a passage from said vessel to said liquid pump, a single discharge passage from said liquid pump for all of the liquid handled by said pump, a throttle valve in said discharge passage, a passage for the air from said vessel to said evacuator, a float in said vessel, and a mechanical drive from said float to said throttle valve for controlling the capacity of said liquid pump by the liquid level in said vessel, thereby maintaining a liquid level in said vessel and also maintaining a vacuum in said vessel.
